The ornamental design for vehicle-wheel front face, as shown and described.

DESCRIPTION

FIG. 1 is a perspective view of a vehicle-wheel front face according to my new design;

FIG. 2 is an enlarged front elevational view thereof;

FIG. 3 is an enlarged side elevational view thereof, it being understood that the opposite side is a mirror image thereof, and,

FIG. 4 is a front elevational view of a second embodiment of my new design, the only difference being the reversed curvature of the wheel spokes.

Portions of the wheel depicted in broken line are for illustrative purposes only, and form no part of the claimed design.
